UNITED STATES PATENT OFFICE

106,367

DESIGN FOR A COMBINED MAGAZINE BINDER, NEWSPAPER HOLDER, AND BOOK RACK

Orren M. Kee, San Antonio, Tex.

Application July 26, 1937, Serial No. 70,671

Term of patent 14 years

To all whom it may concern:

Be it known that I, Orren M. Kee, a citizen of the United States of America, residing at San Antonio, county of Bexar, and State of Texas, have invented a new, original, and ornamental Design for a Combined Magazine Binder, Newspaper Holder, and Book Rack, of which the following is a specification, reference being had to the accompanying drawing, wherein:

Figure 1 is a perspective view of a combined magazine binder, newspaper holder and book rack, showing my new design.

I claim:—

The ornamental design for a combined magazine binder, newspaper holder and book rack, as shown.

ORREN M. KEE.
